US0D1073510S

(12) **United States Design Patent** (10) **Patent No.:** **US D1,073,510 S**
(45) **Date of Patent:** **** May 6, 2025**

(54) **WARNING LIGHT**

(71) Applicant: **Guangzhou Guanmingjie Intelligent Photoelectric Technology Co., Ltd, Guangzhou (CN)**

(72) Inventor: **Yuzhao Liu, Guangzhou (CN)**

(73) Assignee: **Guangzhou Guanmingjie Intelligent Photoelectric Technology Co., Ltd, Guangzhou (CN)**

(**) Term: **15 Years**

(21) Appl. No.: **29/973,619**

(22) Filed: **Nov. 18, 2024**

(30) **Foreign Application Priority Data**

Sep. 14, 2024 (CN) 202430591718.7

(51) LOC (15) Cl. **10-05**

(52) U.S. Cl.

USPC **D10/114.1**

(58) **Field of Classification Search**

USPC D10/104.1, 111, 113.4, 114.1–114.9, 115, D10/121; D26/24, 37, 38, 41, 45, 46, 48, D26/49, 50, 51, 60, 61, 63, 64, 65, 66,

D26/123, 124

CPC F21L 4/005; F21L 4/027; F21L 19/00; G08B 5/36

CLAIM

The ornamental design for a warning light, as shown and described.

DESCRIPTION

FIG. 1 is a top, front and right side perspective view of a warning light, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 7.

The evenly broken lines show the features of the warning light that form no part of the claimed design. The unevenly broken lines illustrate the boundary of the enlarged view that form no part of the claimed design.

1 Claim, 9 Drawing Sheets
